HAND LUGGAGE ATTACHMENT

Daniel Allcott Kelly, Milwaukee, Wis.

Application July 26, 1943, Serial No. 496,098

1 Claim. (Cl. 190—39)

This invention appertains to baggage and more particularly to traveling bags, such as suitcases and similar hand luggage.

Much difficulty is encountered by travelers in carrying heavy hand luggage to and from trains and the like, and due to the scarcity of porters at railroad terminals, women as well as men are subjected to this hardship.

The weight of the bag makes it necessary for the traveler to rest the bag on the ground from time to time while the bag is being carried, and the weight thereof pulls the traveler down on one side, creating an unsightly posture and this is particularly objectionable to women.

It is therefore one of the primary objects of my invention to provide means whereby hand luggage can be easily pulled along the station platform or the street similar to a child's wagon, whereby the travel will not be subjected to the direct weight and pull of the luggage.

Another salient object of my invention is the provision of a suitcase or similar hand bag with ball bearings or wheeled casters or slides on the lower face thereof for movement over the ground and a novel pull handle or strap on one end thereof, so that the bag can be conveniently and easily pulled alongside of the traveler.

A further object of my invention is to provide novel means for arranging the ball bearing or wheeled casters or slides on the lower face of the piece of hand luggage so that the piece of luggage will readily track alongside of the person pulling the same.

A further important object of my invention is the provision of a pull handle hingedly connected to one end wall of the suitcase or bag movable against one wall of the bag when the same is not in use and movable forwardly of the bag to an extended position when in use to permit the easy pulling of the bag or suitcase.

A still further object of my invention is the provision of a pull handle embodying a pair of hingedly connected sections with the outer end of one section hingedly connected to one upper corner of the piece of luggage and the outer end of the other section having a hand grip, the arrangement being such that the handle can be readily moved to an extended position for facilitating the pulling of the case or to a flat collapsed position against one wall of the case when not in use, so as to be out of the way in the normal use of the case.

A still further object of my invention is the provision of a novel pull strap connected at one end to one end wall of the piece of luggage with

means for detachably connecting the strap to the piece of hand luggage at spaced points out of the way when the strap is not being used.

With these and other objects in view, the invention consists of the novel construction, arrangement, and formation of parts, as will be hereinafter more specifically described, claimed, and illustrated in the accompanying drawing, in which drawing:

10 Figure 1 is a perspective view of a suitcase or similar piece of hand luggage showing one form of my novel pull handle connected therewith and swung to an extended position for facilitating the pulling of the bag or case along a station platform.

Figure 2 is an enlarged fragmentary, sectional view taken on the line 2—2 of Figure 1 showing the handle in its collapsed out-of-the-way position against one end wall of the case.

20 Figure 3 is an enlarged, fragmentary, sectional view taken on the line 3—3 of Figure 2 looking in the direction of the arrows showing a resilient detent or latch for holding the handle in its collapsed position against accidental swinging.

25 Figure 4 is a fragmentary, perspective view showing another form of my swinging handle for facilitating the pulling of the suitcase or other piece of hand luggage.

30 Figure 5 is a perspective view showing another form of my pull handle, said form consisting of a flexible pull strap.

35 Referring to the drawing in detail, wherein similar reference characters designate corresponding parts throughout the several views, the letter B generally indicates a traveling bag or similar piece of hand luggage and A one preferred form of my novel attachment therefor.

The traveling bag B can be of any preferred 40 character, size, or shape and will not be described in detail, but the same includes an end wall 5, a bottom wall 6 and a top wall 7. The top wall 7 is provided with a carrying handle 8.

45 My novel attachment A for facilitating the transporting of the bag or other piece of hand luggage from point to point preferably embodies a pull handle 10.

This handle 10 includes inner and outer sections 11 and 12 and can be formed from any desired material, such as, flat strap iron or steel suitably plated to enhance the appearance thereof. The meeting ends of the sections 11 and 12 are hingedly connected as at 13, for swinging movement. The outer end of the inner section 11 is hingedly connected as at 14, to

an attaching face plate 15. This plate 15 is secured to the end wall 5 by means of rivets 16 or similar fastening elements.

As is clearly shown in Figures 1 and 2, the attaching face plate 15 is preferably secured to the end wall 5 adjacent the upper end thereof.

The outer end of the section 12 of the pull handle 10 is provided with any preferred type of hand grip 17.

Normally, the handle 10 is collapsed flat against the end wall 5 of the traveling bag B, as is clearly shown in Figure 2, and when the handle is in its collapsed position, the section 11 lies flat against the outer face of the end wall 5 and the section 12 swings flat against the section 11. To hold the handle in its collapsed position against accidental swinging movement, a latch or detent can be provided. As illustrated in Figures 1 and 3, one edge of the attaching face plate 15 has formed thereon a spring finger 18 and this finger 18 is adapted to snap over the hand grip 17 when the handle is in its collapsed inoperative out-of-the-way position.

When the bag is to be pulled alongside of the traveler, the handle is pulled away from the spring finger 18 and the handle is pulled up to an extended position, as shown in Figure 1. As the handle is hingedly connected to one upper corner of the suitcase or other piece of hand luggage, the hand grip 17 can be conveniently disposed for grasping by the traveler and obviously the handle can be swung up and down to suit varying conditions.

In order that the suitcase or other piece of hand luggage can be conveniently pulled over a surface, the bottom wall 6 thereof is provided with ball bearing casters, wheeled casters or metal slides. I preferably provide ball bearing casters 19, as such type of casters do not take up much space and can be conveniently secured to the lower wall of the suitcase. By referring to Figures 1 and 5 it can be seen that these ball bearing casters are arranged in a novel way on the bottom wall 6 of the case. Thus at the transverse center of the bottom wall of the case two large casters 19 are utilized and the bottom wall adjacent to the ends of the case are provided with relatively small ball bearing casters. These small ball bearing casters are arranged at the longitudinal center axis of the bottom wall of the case. By this arrangement, the bag can be easily pulled by the handle and the bag will readily track alongside of the traveler.

My invention can take different forms, and, as shown in Figure 4, I can utilize a pull handle 20 formed from a single rigid bar of metal or other material. In this instance, one end of the pull handle 20 is connected by a hinge 21 to one upper corner of the bag or other piece of hand luggage. The opposite end of the handle 20 is provided with any preferred type of hand grip 22.

The handle 20 can be held down on the top wall of the bag by a suitable latch, or glove snap fastener 23.

In use of this type of pull handle, the latch or snap fastener 23 is released and the handle is swung on its hinge 21 to a convenient position to be grasped by the traveler so that the bag can be easily pulled alongside of the traveler.

In Figure 5 I have shown a pull handle 25 which is in the form of a flexible strap. This strap can be secured by stitching or the like to the case or bag and in the present instance I have shown one end of the strap securely connected to the bottom wall of the bag and the same is adapted to be folded flat against one end wall of the bag and over the top of the bag when the same is not in use. However, this strap can be secured to one upper corner of the bag (and such is possibly preferable) similar to the rigid handle shown in Figure 4. The outer end of the strap handle 25 is provided with any preferred type of hand grip 26.

The strap is of such a length that the same can be readily grasped by the hand of the traveler in a natural fashion without stooping down.

As is clearly shown in Figure 5, when the strap is not in use the same is folded over one end wall and the top wall of the piece of luggage, as heretofore stated, and the strap can be held down at spaced points flat against the piece of hand luggage by the use of glove fasteners or the like 27. These snap fasteners can be arranged at the most convenient or logical points for holding the strap on the suitcase against movement. The strap can also be provided with a slot or opening 28 for fitting over the carrying handle 8 of the suitcase so that the same will not interfere with the use of said handle 8.

In use of a traveling bag or the like equipped with my novel attachment, the strap 25 is released from the bag by unsnapping the companion sections of the snap fasteners and the hand grip 26 is grasped in the hand of the traveler. The bag or suitcase can now be conveniently pulled along the side of the traveler and naturally this movement is facilitated by the ball bearing or wheeled casters or slides 19.

From the foregoing description it can be seen that I have provided a novel and simple attachment for traveling bags and the like for facilitating the transporting thereof from one place to another.

Changes in details may be made without departing from the spirit or the scope of my invention, but what I claim as new is:

In a suitcase or similar piece of hand luggage, a pull handle for the suitcase including companion elongated flat inner and outer sections, means hingedly connecting the inner ends of the inner and outer sections together, an attaching face plate secured to one end wall of the suitcase adjacent to the upper end thereof, means hingedly securing the outer end of the inner section to said attaching face plate, a hand grip carried by the outer end of the outer section, said handle being movable to an extended operative position forwardly of the case and to a flat inoperative position against the end wall of the case with the inner and outer sections flat against one another in abutting relation, and a resilient finger carried by the attaching face plate for engaging the handle to hold the same against accidental swinging movement when the same is folded flat against said end wall.

DANIEL ALLCOTT KELLY.
